HIGH FREQUENCY BAND FILTER

Klaas Posthumus and Theodorus Josephus Weyers, Eindhoven, Netherlands, assignors to Radio Corporation of America, a corporation of Delaware

Application January 2, 1932, Serial No. 584,434
In Germany June 15, 1931

1 Claim. (Cl. 178—44)

In many cases, for instance, in wireless telegraphy, it is desirable that a more or less wide frequency band passes as freely as possible during the transmission, and that all other frequencies, both the higher and the lower frequencies, are suppressed as much as possible. In apparatus constructed for receiving radio waves it is desirable, moreover, to be able to adjust the average height of the frequency band which is allowed to pass to the carrier wave frequencies of all of the transmitting stations to be received.

According to the present invention this purpose is attained by capacitively coupling two or more tunable oscillatory circuits by means of one or more condensers of such a size that the coupling in or near the middle of the covered frequency range is critical. By "critical coupling" is to be understood in this case a coupling at which the crest of the resulting resonance curve of the coupled circuits begins to sag.

The novel features which we believe to be characteristic of our invention are set forth in particularity in the appended claim, the invention itself, however, as to both its organization and method of operation will best be understood by reference to the following description taken in connection with the drawing in which we have indicated diagrammatically one circuit arrangement whereby our invention may be carried into effect.

The invention will be more clearly understood by reference to the accompanying drawing, representing by way of example, a form of construction thereof used in the antenna circuit of a receiving set.

The antenna 1 is connected to earth through an antenna condenser 2 and a coil 3. A tuning condenser 4 and a fixed coupling condenser 5 are connected in parallel to the coil 3. The condenser 5 couples the oscillatory circuit 3, 4, 5 to a second tunable oscillatory circuit 5, 6, 7 whose variable condenser 6 is mechanically connected to the condenser 4. The oscillating end of the coil 7 is connected to the control grid of an electron discharge tube 8, for example, a high frequency or detector valve of the screen grid type.

The condenser 5 is given such a size that if both condensers 4 and 6 occupy almost their center position, both circuits 3, 4, 5 and 5, 6, 7 are coupled together critically. The invention may be of particular use for receiving wireless telephony and may moreover be used in all cases in which a definite frequency band must be filtered from a large range without one or more frequencies inside this band being privileged.

The coupling between the two tuned circuits is capacitive, thus by increasing frequency the coupling decreases. The value of the coupling capacity is thus chosen, that for the frequency at the middle of the frequency range, the coupling is critical.

What is meant by "critical coupling" may be declared as follows:

If two tuned circuits are coupled very loosely, the resultant characteristic of the system shows one peak, the height of which increases with increasing coupling until the "critical coupling" is reached, a tighter coupling than this "critical coupling" causes a resonance curve with two peaks, the height of which is about constant and the distance between the peaks being greater for tighter coupling of the circuits.

The "critical coupling" of two given circuits is thus a definite coupling and when this coupling is caused by a capacity, also the magnitude of this capacity is known, this being solely dependent on the magnitude of the impedances which the circuits contain.

The advantage of using a capacitive coupling is the following:

If the coupling is increased above critical the peaks of the resonance curve are more separated, but at the same time the slope of the sides of the resonance curve is steeper (because each of the resonance curves of the separate circuits is narrower for lower frequencies and for these the coupling of the circuits is tighter). This results in a resonance curve which has equal width for different frequencies.

The best results are obtained when using a capacitive coupling which is critical in the middle of the frequency range. If the coupling would be made critical for one of the lowest frequencies to be transmitted, the coupling for the highest frequencies would be so small that the energy transfer is too much decreased.

If on the other hand the coupling is made critical for one of the highest frequencies, the coupling for the lowest frequencies is so tight that the resonance curve shows a deep sag in the middle, which should also be avoided.

If the coupling is critical in the middle of the frequency range, a frequency band of practically constant width may be transmitted with equal strength, neither a too loose, nor a too tight coupling with its inherent disadvantages ever being obtained.

While we have indicated and described one system for carrying our invention into effect, it will be apparent to one skilled in the art that our in-

vention is by no means limited to the particular organization shown and described, but that many modifications may be employed, without departing from the scope of our invention as set forth in 5 the appended claim.

What is claimed is:

In combination, in a radio receiver, a screen grid amplifier tube, a signal circuit adapted to have impressed thereon side band modulated carrier frequencies of a predetermined frequency range, a tunable band pass network coupling said circuit to the input electrodes of the tube, said network comprising a pair of oscillation circuits each including a coil and a variable tuning condenser, a coupling condenser common to both oscillation circuits, said signal circuit being connected across one of said coils and said input electrodes being connected across the other coil, 10

a mechanical uni-control device for adjusting the adjustable elements of said condensers to tune said oscillation circuits through said range, said coupling condenser having its coupling impedance arranged to pass through the point of critical coupling substantially at the mid-point of the network tuning range, and said coupling condenser having a capacity magnitude such that the crest of the resonance curve of said network begins to sag when said adjustable elements are 10 positioned substantially at their median positions whereby the average height of the modulated frequency band which is transmitted through the network is adjusted to the carrier frequencies of said range. 15
